UNITED STATES PATENT OFFICE.

ROBERT L. FRINK, OF CLEVELAND, OHIO.

METHOD OF AND APPARATUS FOR DRAWING GLASS.

1,165,961.

Specification of Letters Patent. Patented Dec. 28, 1915.

Application filed July 24, 1908. Serial No. 445,077.

To all whom it may concern:

Be it known that I, ROBERT L. FRINK, a citizen of the United States, resident of Cleveland, county of Cuyahoga, and State of Ohio, have invented a new and useful Improvement in Methods of and Apparatus for Drawing Glass, of which the following is a specification, the principle of the invention being herein explained and the best mode in which I have contemplated applying that principle, so as to distinguish it from other inventions.

In spite of the fact that attempts have been made over a considerable period of time to draw glass cylinders or "rollers" by mechanical means instead of manually, there have been serious difficulties encountered even in the most recent and improved types of apparatus. These are believed to be largely attributable to the character of the operation itself, which it will be appreciated is one of extreme delicacy, so that to replace the manipulation of a skilled workman with mechanical devices, involves a consideration of all the details of operation comprehended in the art of drawing glass. No small amount of the trouble heretofore experienced with apparatus of the class in hand, it would seem may be ascribed to attempts in such apparatus, and the methods exemplified in their operation, to act upon or influence the bath of molten glass from which the cylinder or "roller" is drawn, or to similarly affect the roller itself, particularly during its formative stage. This remark applies equally to methods and apparatus for artificially controlling the temperature, and thereby the consistency, of the metal in the bath, as also to methods and apparatus for similarly artificially regulating the supply of air to the cylinder as it is drawn, and to the controlling of the temperature of such cylinder at or near the drawing point with the object of varying its thickness. In various types of apparatus which I have recently devised relating to this same problem of drawing glass, a general disclosure of such apparatus being made in my Patent No. 846,102, dated March 5, 1907, I have proceeded upon a different

theory, namely that of making the apparatus so "elastic" in its various parts as to accommodate the same to the material being handled, and to the incidents of the drawing operation. The present apparatus, which relates to an improvement in that disclosed in the patent just named, is illustrative of this principle in the several details of such improvement. In addition there are other minor features of more or less importance included therewith, all having in view the object of facilitating the drawing of glass cylinders, and the production of a product of uniform and marketable character.

To the accomplishment of the above and related objects, said invention, then, consists of means hereinafter fully described and particularly pointed out in the claims.

The annexed drawings and the following description set forth in detail certain means for carrying out the invention, such disclosed means constituting, however, but one of various ways in which the principle of the invention may be used.

In said annexed drawings: Figure 1 is a front elevational view of apparatus for drawing glass cylinders embodying my several improvements; Fig. 2 is a vertical section, and a part side elevation of such apparatus; Fig. 3, is a plan view of the drawing pot, or receptacle, and the casing inclosing the same; Fig. 4 is a sectional view of a portion of the air-supply mechanism forming the lower portion of the apparatus shown in Fig. 2; Fig. 5 is a detail of such air supply mechanism; Fig. 6 is a horizontal sectional view of the same detail on the line 6—6 Fig. 5; Fig. 7 is a view, part side elevation, and part section, of the drawing rolls, and appurtenant parts; Fig. 8 is a transverse sectional view of one of said rollers, the plane of the section being indicated by the line 8—8, Fig. 7; and Figs. 9 and 10 illustrate a modified construction of head.

In such drawings the glass melting furnace A, which may be of any suitable character, appears in Fig. 1, only, being there shown in front elevation; the drawing pot or receptacle B, with which the apparatus

in hand is more particularly associated, appears however, in both the figure named, and in Figs. 2 and 3. Communication is had between the furnace and such pot 5 through a passage or conduit A' as shown, a suitable gate or like means being interposed in such passage, whereby the flow of molten glass may be stopped when desired. The drawing mechanism proper comprises 10 a set of rollers D, shown as being two in number in the case in hand, and located directly above the drawing pot B just described. The cylinder or "roller" being drawn is pressed between these rollers and 15 drawn upwardly once it has been started. Rising upwardly through an opening b in the bottom of the drawing pot or receptacle to a short distance above the contemplated level of molten glass therein, is a drawing 20 head B' around which the cylinder is drawn, and by means of which taken in conjunction with an air supply that is furnished through said head the diameter of such cylinder is regulated. The general operation 25 of the drawing mechanism, the principal parts of which have been referred to, need not be further noted in this connection, than to state that the air thus supplied through the head is discharged into the 30 lower portion of the cylinder being drawn, from whence it escapes around such head by distending the plastic cylinder walls a greater or less degree, as is fully described in the aforesaid Letters Patent No. 846,102. 35 It being with improvements in the drawing pot, the drawing head, and air supply mechanism connected therewith and the drawing rolls that the present invention is concerned, the details of each of these parts 40 in their present improved form will now be taken up in their order.

The drawing pot which I show, Figs. 2 and 3, is of general cylindrical form, and is provided on one side with an inlet opening 45 b' wherewith the conduit A' leading from the furnace is connected. Suitably supported in the pot just above the inlet opening in question, is a horizontal partition b² provided with an aperture b³ through which the 50 molten glass flowing in from the conduit may escape into the upper portion of the pot. The support B² for the drawing head, the structure of which will be taken up presently, extends up through the bottom of such 55 pot, and through the aperture in such partition, but is located off center with respect to such aperture, so as to leave the narrower space on the side thereto nearest the inlet opening b'. By reason of this arrangement 60 an unequal diversion of the glass passing through such aperture will obviously be effected and by properly relating the space left on the different sides of the drawing head support B², the flow of hotter metal

which would naturally tend to rise for the 65 most part on the nearest side of the support will be forced to take the longer path by way of the other side of such support, and in this manner a substantially uniform consistency of metal at the several points, defining the base of the cylinder being drawn, 70 can be secured. The transverse partition b² is so secured as to be removable when occasion arises for cleaning the pot of its contents. The general method of, and another 75 construction of pot for, thus securing a proper consistency of metal for the drawing operation, it should be stated, forms the subject matter of a co-pending application, Serial No. 439,767, filed June 22, 1908. 80

The pot B as in the case of my earlier apparatus, is inclosed in a casing B³ of brick work, or the like, preferably insulated therefrom by an interposed layer of suitable material such as asbestos, (not shown). Instead however, of building up such casing directly on the foundation or frame work A² in front of the furnace A, I divide the same into sections, preferably two, the line of division passing through the support B² 90 of the drawing head and the conduit A' for supplying the molten glass to the pot. These sections are then mounted on movable supports conveniently in the form of heavy trucks, provided with rollers b⁴ mounted on 95 suitable rails a resting on frame work A², whereby the casing sections may be approached to, or removed from, the drawing pot, as desired. Such pot, as well as the drawing head, being supported independently of the casing, they will be left standing in readily accessible condition by simply drawing to one side the casing sections in question. 100

The support B² for the head around which 105 the cylinder, or other hollow article is drawn, comprises two concentric pipes b⁵ b⁶, Fig. 2, constructed of suitable material to resist the temperatures to which they are exposed when surrounded by the metal in pot B. The 110 head B' is mounted on the upper end of the aforesaid pipes, and is likewise constructed of suitable heat resisting material, such as fire-clay or the like. The form of the head is conical or funnel-like, a central aperture 115 b⁷ therein being connected as shown with the inner of the two pipes of the support. In the base of the head there is formed an annular chamber b⁸ surrounding such central aperture, and provided with lateral ports b⁹ 120 such chamber having communication with the outermost of the two pipes. Air under pressure is designed to be supplied to the head through such outer pipe b⁵, while on the contrary suction means are designed to 125 be connected with the inner pipe b⁶, as a result of which it will be seen that in effect, a circulation of air is maintained, through the

lower section of the cylinder or roller, as indicated by the arrows in Fig. 2. In addition it is contemplated that the suction may be made strong enough to withdraw air more rapidly from such lower cylinder portion than it is supplied through the head, by which means a stream of air will be drawn downwardly through the upper portion of the cylinder, independently of the drawing operation entirely. Such stream of air may be made of sufficient volume to exercise a perceptible cooling effect on the upper portion of the cylinder if found desirable.

For supplying air to outer pipe b^5 , and withdrawing air from the inner pipe b^6 , suitable blower and suction mechanism is provided below the lower ends of such pipes, being preferably mounted on a movable base C, and detachably connected with the pipe ends, as at c, so that in the event of the drawing pot or receptacle and its surrounding casing being taken apart for the purpose of renewal or repair, such mechanism can be removed entirely from the scene of operation, and any injury thereto avoided. The air-supply mechanism comprises a supply pipe c' a drum c^2 laterally connected with said supply pipe, and a blower C' having its delivery pipe c^3 extending through said drum, and opening laterally into the same, Figs. 2 and 4. Weighted escape valves c^4 c^5 are provided for the upper end of blower pipe c^3 which extends above the drum, and for an opening c^6 in said drum located in its side, substantially opposite the supply pipe c' . The aperture in this supply pipe may be regulated by means of a gate valve c^7 which is shown as having a rectangular opening c^8 coöperative with a similar opening c^9 in a diaphragm c^{10} disposed across the pipe aperture. By reason of the form of such openings c^8 c^9 and their relative disposition, leaving the opening rectangular in shape, whatever its size, the adjustment of the valve to provide any determinate aperture that may be desired, is readily accomplished. Of course, any form of diaphragm or other valve, may be used to accomplish this result. A gate valve c^{11} is also provided in the lower delivery pipe intermediately between the blower and the drum. The suction mechanism comprises simply a suction fan C² connected with the lower end of the inner pipe. Motors C³ C⁴ mounted on the same base C are conveniently used to drive the blower and suction fans respectively.

Where the rate of withdrawal of the air from the cylinder is a matter of consequence, suitable regulating means (not shown) will be provided in connection with such suction fan, as will be readily understood. By means, however, of the apparatus connected with the blower fan I am enabled to supply

a substantially constant volume of air to the portion of the cylinder between the drawing head and the bath of metal in the pot. By thus supplying a constant volume of air, no regulation is required in this connection, since the volume of the air confined in such lower portion of the article is automatically regulated by the article being drawn itself, as fully described in the patent above named. In operation just sufficient pressure is maintained in delivery pipe c^3 to raise the weighted valves c^4 c^5 ; with the pressure in the drum thus constant the volume of air supplied through pipe c' to the cylinder will be constant for any particular size of aperture.

A separate blower and exhaust mechanism may be provided for each drawing apparatus as suggested in Fig. 2, or by simply prolonging the drum c^2 as indicated in Fig. 1, connection may be made between the same and a plurality of drawing heads. In such case, however, the mechanism in question could not be conveniently supported on a movable base but would require to be permanently installed.

The central aperture b^7 in the drawing head B' taken in conjunction with the funnel-shape of such head, serves an additional purpose to that of affording connection between the exhaust fan and cylinder, namely, any small fragments of glass or other material such as are apt to fall within the cylinder will be prevented from reaching the bath, but will instead be gathered within such head and if small enough withdrawn by the suction entirely from the apparatus.

Since the drawing pot and its inclosing casing together with the other parts associated therewith are not, as has been seen, permanently installed, but on the contrary rendered, for reasons of convenience, separable and removable, I find it desirable to provide additional means of adjustment in connection with the drawing rollers D over the means previously shown. I accordingly so mount the support D' for said rollers, and the driving gear connected therewith, as to render the same adjustable in each of two angularly related directions. To this end said support is mounted on ways d found in blocks d^8 that are adapted to be secured in any predetermined position on other transverse ways d^2 . By means of the adjustment thus rendered possible, the drawing rollers can be centered over the drawing head when the latter has been finally secured in position. In order to adapt the drawing rollers to the drawing of different sizes of cylinders, I have likewise modified their construction, although still retaining their former feature of a yielding periphery d^4 adapted to grip the article being drawn. This periphery, the material construction of

which need not be noted, forming no part of the present disclosure, is fixedly attached to the end members d^5 of the roller, such end members being in the form of disks mounted on a tubular shaft d^6 with which the driving mechanism D^2 is connected through a bevel gear d^7 on one of said members. Rotatably mounted within such tubular shaft, is a second shaft d^8 having oppositely threaded portions, upon which are mounted nuts d^9 slidably held in such tubular shaft and connected through a longitudinal slot d^{10} therein with disks d^{11} corresponding in shape and size with the end members, but movably mounted on said tubular shaft. By rotation of said threaded shaft, which may be effected from a hand wheel D^3 and suitable intermediate gearing d^{12} , as shown, it will be obvious that the two slidably mounted disks d^{11} 15 may be brought together or moved apart as desired, thus varying the length of the portion of the periphery of the roller that is left to flexibly engage the article being drawn.

20 25 So sensitive to changes in temperature is the "roller" or cylinder in its formative stage, that is before the glass has set, that the lower, more or less plastic, portion thereof will be perceptibly thickened by even a slight draft of air across the pot or drawing vessel. The increased surface tension of the bath that gives rise to this phenomenon, will at the same time have a tendency to displace the base of the cylinder, drawing the same, 30 35 in other words, toward the side affected in the manner just described. To accommodate such shifting of the cylinder base, I accordingly introduce an adjustment into the drawing head whereby it may be supported a trifle to one side of the pot in any desired radial direction. Such adjustability is conveniently attained, see Figs. 9 and 10, by mounting the head B' eccentrically with respect to its support B^2 , which has been 40 45 seen to rise substantially centrally within the pot, and at the same time having said head rotatable about such support.

50 55 The foregoing several improvements in my glass-drawing apparatus will, it is believed, add materially to the success of the process exemplified in the operation of such apparatus. Such improvements it will be observed are for the most part contributory to the accomplishment of the general object 60 65 70 75 80 85 90 95 100 105 110 115 120 125 130 135 140 145 150 155 160 165 170 such product appears fair in the initial stages of its manufacture.

65

Other modes of applying the principle of my invention may be employed instead of the one explained, change being made as regards the mechanism herein disclosed, provided the means stated by any one of the following claims or the equivalent of such stated means be employed.

I therefore particularly point out and distinctly claim as my invention:

1. The herein described improvements in drawing glass cylinders, which consists in forcing air into the cylinder during the drawing operation, positively sucking out a portion of the air to regulate the internal air pressure, and controlling the amount of air sucked out independently of the amount of air supplied.

2. In apparatus for drawing glass, the combination with means for supplying air thereto incidentally to the drawing operation, of other means for simultaneously and positively withdrawing air therefrom.

3. In apparatus for drawing glass, a drawing pot or receptacle, a head around which the hollow glass article is drawn, and means for drawing air downwardly through the upper portion of said article.

4. In apparatus for drawing glass, a drawing pot or receptacle, a head around which the hollow glass article is drawn, said head being of such a size as to substantially close such article, means for supplying air to the portion of said article between said head and the bath, and air suction means connected to withdraw air from said article at a point immediately above said head.

5. In apparatus for drawing glass, a drawing pot or receptacle, a head around which the hollow glass article is drawn, two pipes, one within the other, supporting said head, and opening, the one into the portion of said article between said head and the bath and the other into the portion of said article above said head, air supply means connected with said first pipe, and air suction means connected with the second.

6. In apparatus for drawing glass, a drawing pot or receptacle, a funnel-shaped head around which the hollow glass article is drawn, said head being formed with an annular chamber surrounding the central opening therein and provided with lateral escape ports, two pipes, one within the other, supporting said head and respectively connected with the annular chamber and central opening therein, air supply means connected with said first pipe, and air suction means connected with the second.

7. In apparatus for drawing hollow glass articles, the combination of a drawing pot or receptacle, a head around which the hollow

low glass article is drawn, and a support for said head rising substantially centrally above said pot, said head being eccentrically mounted with respect to said support and 5 rotatable with respect to said pot.

8. In apparatus for drawing hollow glass articles, the combination of a drawing pot or receptacle, a head around which the hollow glass article is drawn, and a support for

said head rising substantially centrally above 10 said pot, said head being eccentrically mounted with respect to said support and rotatable about the same.

Signed by me, this 18th day of July, 1908:
ROBERT L. FRINK.
